METHOD OF EROSION CONTROL

Application filed June 24, 1931. Serial No. 546,442.

My invention relates to improvements in methods of erosion control.

The object of my invention is to provide a novel, cheap and efficient method of working ground to effect the gradual elimination of steep deep gullies while at the same time reducing injurious erosion in the area treated.

The novel features of my invention are hereinafter fully described and claimed.

10 In the accompanying drawings, which illustrate the treatment of a gully by my improved method,

Fig. 1 is a cross section through a gully that is designed to eliminate, after the laying 15 along the bottom thereof of farm draining tiling, and prior to the removal of edge and surface portion at opposite sides of the gully.

Fig. 2 is a view similar to Fig. 1 as the gully appears after the first cycle of operations

20 Fig. 3 is a view similar to Fig. 2 showing the conditions following the second cycle of operations.

Fig. 4 is a view similar to Fig. 3 showing the gully filled following the third cycle of operations.

Similar characters of reference designate similar parts in the different views.

In carrying my improved method into effect, a line of farm draining tiling 1 is laid along the bottom of a gully 2 which is to be filled. Such line of tiling, of the type named, is laid in the usual manner such as will permit drainage into the tiling between 35 its joints.

In the first cycle of operations, as begun after the laying of the tiling, edge and surface earth portions are removed for a pre-determined distance at opposite sides of the 40 gully 2.

Said removed portions are taken from the spaces between the dotted and solid lines at opposite sides of the gully 2, Fig. 2. The portions so removed are deposited in the 45 gully upon the tiling 1, and are designated by 3.

The upper surface of said deposit 3 is then grased by depositing thereon the sod removed with the portions removed, by sowing 50 grass seed thereon, or with the natural

growth that will spring from the surface of the deposit.

The deposit 3 is permitted to stand without further operations until the ground becomes settled and compact and the grased surface has become set and the grass well rooted and extending above the surface. This may be for a term of several months.

The grased surface will catch and hold some of the earth brought into the gully by storm water. Such storm water, designated by 4, as does not run out of the gully will seep through the deposit 3 and will enter and be carried away by the tiling 1. Such seepage will assist in compacting the deposit 3 in the gully 1.

In the second cycle of operations, which is begun after the 1st deposit 3 has become compact and well grased, the edge and surface earth portions are removed at opposite 70 sides of the gully for a wider distance than in the first earth removal, the earth being taken from the spaces between the dotted and solid lines at opposite sides of the gully in Fig. 3. The earth last removed is deposited in the gully upon the deposit 3 forming the deposit 5.

The surface of the deposit 5 is then grased after the manner described with reference to the grassing of deposit 3, and permitted to stand for a time sufficient for the compacting of the last deposit and for the grased surface to set and the grass rooted and extending above the surface.

The cycles above described are consecutively repeated, the removal of earth at each cycle being extended to a wider extent than was the earth removal in the next preceding cycle.

These cycles of operations are continued until the gully has become filled and the surface of the ground at opposite sides of the gully is even, as shown in solid lines in Fig. 4. In Fig. 4 the conditions are illustrated as they exist following the third cycle of operations, in which the earth removed from the spaces between the dotted and solid lines at opposite sides of the gully, and distant therefrom, was deposited in the gully on top of the deposit 100

5, the last deposit being designated by 6, in
Fig. 4.

By means of the cycles of operations
hereinbefore described, a gully may be cheap-
ly filled, while at the same time controlling
the injurious erosion caused by storm water
following the gully.

By reason of the time permitted to elapse
10 between the different cycles of operations, the
earth deposited in the gully is much more
solid and compact and not so subjective to
erosive action of storm water than would
earth deposited at one time in quantities suffi-
15 cient to fill the ditch or gully, and which
would not contain the succeeding layers of
sodded surfaces, as are present in the earth
deposited in the gully and treated in the man-
ner employed in carrying my improved
20 method into effect.

20 Such layers of sodded surfaces tend to bind
and hold the earth deposited in the gully after
the same has become filled, as well as serving
to prevent injurious erosive action on the
deposits between the different cycles of opera-
25 tions.

I do not limit my invention to the precise
steps described, as modifications thereof,
within the scope of the appended claims, may
30 be made without departing from the spirit of
my invention.

What I claim is:—

1. The method of erosion control consist-
ing in removing edge and surface earth por-
35 tions for a predetermined distance at oppo-
site sides of a gully, depositing such removed
portions in the bottom of said gully, grassing the
surface of such deposit, then, after said
grassed surface has become set and rooted,
40 removing further edge and surface earth por-
tions for a wider distance at opposite sides of
said gully than in the first instance of earth
removal, depositing the last removed earth
portions on the first deposit, grassing the sur-
45 face of the last deposit, then, after the last
grassed surface has become set and the grass
thereon rooted, continuing consecutively in
cycles and in the order above named the re-
moval of edge and surface portions, the de-
50 positing in the gully on the previous deposit
of such removed earth portions, grassing the
surface of the deposits, and permitting such
grassed surfaces to become set and rooted, at
each cycle extending the width of surface
55 earth removals beyond that of the next pre-
ceding earth removal until the gully has be-
come filled.

2. The method of erosion control consisting
in laying along the bottom of a gully a line
60 of farm draining tiling, removing edge and
surface earth portions for a predetermined
distance at opposite sides of a gully, deposit-
ing such removed portions on said tiling,
grassing the surface of such deposit, then,
65 after said grassed surface has become set and
the grass rooted, removing further edge and

surface portions for a wider distance at oppo-
site sides of said gully than in the first in-
stance of earth removal, depositing the last
removed earth portions on the first named
deposit, grassing the surface of the last de-
70 posit, then, after the last grassed surface has
become set and the grass rooted, continuing
in consecutive cycles in the order above named
edge and surface earth removals for a wider
75 distance at each succeeding cycle, depositing
such removed earth on the next preceding
deposit, grassing the surface of each deposit,
and permitting the grassed surfaces to be-
come set and the grass rooted, until the gully
80 has become filled.

In testimony whereof I affix my signature.
ISAAC T. CURD.
